UNITED STATES PATENT OFFICE.

JAMES E. AUSTIN, OF BINGHAMTON, NEW YORK, ASSIGNOR TO CENTRAL FLATIRON MFG. CO., OF BINGHAMTON, NEW YORK, A CORPORATION.

SAD-IRON.

1,094,869.

Specification of Letters Patent. Patented Apr. 28, 1914.

Application filed January 18, 1910. Serial No. 538,591.

To all whom it may concern:

Be it known that I, JAMES E. AUSTIN, a citizen of the United States, and a resident of Binghamton, in the county of Broome and State of New York, have invented a new and Improved Sad-Iron, of which the following is a full, clear, and exact description.

The invention relates to said irons heated by burning gas, such, for instance, as shown and described in the Letters Patent of the United States, No. 851,479, granted to me April 23, 1901.

The object of the present invention is to provide certain new and useful improvements in sad irons, whereby the size of the mixing chamber for the gas and air can be enlarged or reduced at the will of the operator, the burning gas is utilized to the best advantage and all danger by back firing is completely prevented and the usually unsightly chimney is dispensed with. For the purpose mentioned, the sad iron is provided with an adjustable mixing chamber, connected at the outer end with a gas supply and opening at its inner end into the hollow body of the said iron.

A practical embodiment of the invention is represented in the accompanying drawings forming a part of this specification, in which similar characters of reference indicate corresponding parts in all the views.

Figure 1 is a perspective view of the sad iron; Fig. 2 is a longitudinal central section of the same; Fig. 3 is a sectional plan view of the same on the line 3—3 of Fig. 2; and Fig. 4 is a cross section of the same on the line 4—4 of Fig. 2.

The body A, of the sad iron is shown as of the usual shape and made of two castings, one of which is hollow and comprises the bottom A' and the sides A², which converge and meet at the front of the body, and the other casting comprises the top A³ and the rear end A⁴, the two castings being securely fastened together by screws B. On the upper surface of the top A³ rest the lugs C' of a protecting plate C, fastened in position by a bolt D, engaging the plate C and the top A³, as plainly indicated in the drawings. From the front and rear ends of the protecting plate C rise standards C², connected with each other by a bolt E, carrying the handle F, preferably made of wood or other suitable material. The sides

A² of the hollow body are provided near the front end at the top with outlet openings A⁵, covered by a perforate plate G, fitted against the inner surface of the hollow body and resting at its lower edge on shoulders A⁶, formed on the inner surface of the hollow body, the top edge of the plate G being engaged by the under surface of the top A³, to securely hold the plate G in place without other fastening devices. The rear end A⁴ is provided with openings for the passage of air to the interior of the hollow body, and on the said end A⁴ is formed a boss A⁷, in which is adjustably held a bushing H, by the use of a set screw I, screwing in the boss A⁷ against the bushing H. The bushing H is inclined in a downward and forward direction, and its inner end is covered by a perforate cap H', preferably in the form of a wire netting, to prevent back flashing of the burning gas in the hollow body. On loosening the set screw I, the bushing H can be moved inward or outward in the boss A⁷, so as to bring the inner end of the said bushing nearer to or farther from a transverse lug A⁸, located on the upper surface of the bottom A', a distance from the rear end or heel of the sad iron, as plainly indicated in Fig. 2. The bottom A', from the lug A⁸ to the front end thereof, is preferably provided with corrugations A⁹.

In the bushing H is mounted to slide a mixing chamber J, open at the front end and connected at its rear end with a pipe K, adapted to be connected by a rubber tube with a gas supply, and on the said pipe K is arranged an air admission valve L, for controlling the admission of air to the pipe K, to form a mixture of air and gas to be burned in the hollow body of the sad iron. This valve L is preferably of the same detail construction as the one shown in the patent above referred to, so that further description of the same is not deemed necessary.

From the top A³ of the hollow body depends a lug A¹⁰, to the under side of which is secured a deflector N, in the form of a plate, inclined downwardly and forwardly, and extending from the rear end A⁴ to the front end of the hollow body. The deflector N is provided at the sides with upturned flanges N', spaced from the sides A² of the hollow body and extending to the under side of the top A³. By this arrangement, the ex-

pansion chamber which extends between the bottom A' and the deflector N is increased by the addition of the space formed between the flanges N' and the sides A^2 of the hollow body, as will be readily understood by reference to Fig. 4.

When it is desired to use the sad iron, the valve L is preferably closed and the gas turned on, so that the gas passes by way of 10 the pipe K , the mixing chamber J and the perforate cap H' into the combustion chamber of the hollow body, at which point the gas is ignited by a match or other lighting device, passed into the hollow body through 15 the openings in the end plate A^4 . When the gas is burning, the valve L is opened, so as to permit air to enter the pipe K and mix with the gas, the mixture being very intimate, by the use of the mixing chamber J , which is larger than the pipe K , and can be 20 enlarged in size or diminished by correspondingly sliding the mixing chamber J outward or inward in the bushing H .

It is understood that when the gas is 25 burning in the combustion chamber of the hollow body, suction is created in the mixing chamber J , and as the latter is larger than the pipe K , the entering air and gas are free to expand and thus become intimately mixed 30 in the chamber J prior to passing through the perforate cap H' into the chamber, to be burned therein.

It is understood that the transverse lug A^8 serves to spread the flame in a transverse 35 direction, so that the flame reaches all parts of the bottom A' ; and by having the deflector N inclined in a downward and forward direction, the flame is forced into contact with the bottom A' throughout, the end 40 thereof, prior to the products of combustion rising in the front end of the hollow body, to finally pass through the perforate plate G and the outlets A^5 to the outer air. It is further understood that the deflector N confines 45 the most heat in the lower portion of the hollow body, thus evidently heating the bottom A' desired to be heated, and at the same time the deflector N protects the top A^3 against undue heat, to shield the operator's hand having hold of the handles F , the hand being also protected from undue 50 radiation of heat by the plate C spaced from the top A^3 , to allow circulation of air all around the plate.

55 By the use of the perforate cap H' , all danger of back flashing of the flame is prevented.

Having thus described my invention, I claim as new and desire to secure by Letters 60 Patent:

1. A sad iron comprising a hollow body having a tubular and upwardly inclined boss at its rear end and a transverse projection on the inner face of its bottom adjacent to said 65 rear end, and a burner and mixing chamber

consisting of two telescoping tubular members, one of which is adjustably secured in the boss and is provided with a perforated covering at its inner end, and with the other of which, a gas supply is adapted to be connected. 70

2. A sad iron, comprising a hollow body, a boss at the rear end of the said body and inclined in an upward and rearward direction, a bushing in the said boss and provided at 75 its forward end with a perforate covering, a sleeve slidably engaging the said bushing, and a pipe connected with a gas supply and having an air admission valve for controlling the admission of air to the gas in the 80 said pipe, the said pipe being connected with the outer end of the said sleeve.

3. A sad iron, comprising a hollow body, a boss at the rear end of the said body and inclined in an upward and rearward direction, 85 a bushing in the said boss and provided at its forward end with a perforate covering, a screw screwing in the said boss against the said bushing for adjustably securing the bushing in place in the boss, a sleeve slidably 90 engaging the said bushing, and a pipe connected with a gas supply and having an air admission valve for controlling the admission of air to the gas in the said pipe, the said pipe being connected with the outer end 95 of the said sleeve.

4. A sad iron, comprising a hollow body having outlets at the sides of the front and having openings at the rear end, a burner extending through the rear end of the said 100 body, and a deflector arranged within the said hollow body intermediate the top and bottom thereof, the rear end of the deflector extending to the said rear end openings, and the forward end of the deflector being 105 below the said outlets at the sides of the hollow body.

5. A sad iron, comprising a hollow body having outlets at the sides of the front and having openings at the rear end, a burner 110 extending through the rear end of the said body, and a deflector arranged within the said hollow body intermediate the top and bottom thereof, the rear end of the deflector extending to the said rear end openings, and 115 the forward end of the deflector being below the said outlets at the sides of the hollow body, the said deflector being provided at the sides with upturned flanges spaced from the sides of the said body. 120

6. A sad iron, comprising a hollow body provided at its front with an outlet, a burner at the rear end of the said body, and a deflector within the said body and provided at the sides with upturned flanges spaced from 125 the sides of the said body.

7. A sad iron, comprising a hollow body provided at its front with an outlet, a burner at the rear end of the said body, and a deflector within the said body and provided at 130

the sides with upturned flanges spaced from the sides of the said body, the said flanges terminating adjacent the said outlet.

8. A sad iron, comprising a hollow body provided at its front with an outlet, a burner at the rear end of the said body, and a deflector within the said body and provided at the sides with upturned flanges spaced from the sides of the said body, the said deflector being inclined downwardly and forwardly.

9. A sad iron, comprising a hollow body, having outlets at the sides of the front end and having openings at the rear end, a perforate covering for the said outlets, a bushing 15 adjustably held on the said rear end of the hollow body and inclined downwardly and forwardly, the forward end of the bushing having a perforate covering, a sleeve 20 slidable in the said bushing and connected with a pipe for connection with a gas supply, an air admission valve on the said pipe, and a deflector arranged with the said hollow body intermediate the top and bottom thereof, the said deflector being inclined forwardly and downwardly and provided at the 25 sides with upturned flanges extending to the top of the hollow body and terminating adjacent to the said side outlets.

10. A sad iron, comprising a hollow body, provided at its front with an outlet, a burner at the rear end of the said body, and a deflector within the said body and having its

sides spaced from the sides of the said hollow body, flanges between the sides of the deflector and the top of the hollow body, the 35 said deflector being above the said burner to form an expansion chamber between the bottom of the hollow body and the said deflector, the expansion chamber being increased by the addition of the space between the 40 said flanges and the sides of the hollow body.

11. A sad iron, comprising a hollow body provided at its front with outlets, a burner at the rear end of the said body, and a deflector within the said body and having its sides 45 spaced from the sides of the said hollow body, flanges between the sides of the deflector and the top of the hollow body, the flanges terminating at their forward ends adjacent to the said outlets, the said deflector being above the said burner to form an 50 expansion chamber between the bottom of the hollow body and the said deflector, the expansion chamber being increased by the addition of the space between the 55 said flanges and the sides of the hollow body.

In testimony whereof I have signed my name to this specification in the presence of two subscribing witnesses.
